UNITED STATES PATENT OFFICE.

OTTO F. FOGELSTRAND, OF KENSINGTON, CONN., ASSIGNOR TO HART,
BLIVEN & MEAD MANUFACTURING COMPANY, OF SAME PLACE.

DESIGN FOR SHUTTER-HOOK.

Specification forming part of Design No. 7,244, dated March 17, 1874; application filed March 7, 1874.
[Term of Patent 7 years.]

To all whom it may concern:

Be it known that I, OTTO F. FOGELSTRAND, of Kensington, in the county of Hartford and State of Connecticut, have invented and produced a new and original Design for a Shutter-Hook, of which the following is a specification:

The nature of my design is fully represented in the accompanying drawing, to which reference is made.

The contour of the base-plates B B is com-

posed of four curved lines meeting so as to form a rosette. The caps C C are round, and have a flat front ornamented with raised work. The front and rear sides of the hook D are also ornamented in relief.

I claim as my invention—

The design for a shutter-hook, as shown.

OTTO F. FOGELSTRAND.
